(57) **CLAIM**

The ornamental design for a full body resistance bar with wheels, as shown and described.

DESCRIPTION

FIG. 1 is a perspective view of a design for a full body resistance bar with wheels showing our new design.

FIG. 2 is a front elevational view of the full body resistance bar with wheels shown in FIG. 1.

FIG. 3 is a rear elevational view of the full body resistance bar with wheels shown in FIG. 1.

FIG. 4 is an enlarged fragmentary view of the full body resistance bar with wheels as shown in FIG. 3.

FIG. 5 is a left side elevational view of the full body resistance bar with wheels shown in FIG. 4.

FIG. 6 is a right side elevational view of the full body resistance bar with wheels shown in FIG. 4.

FIG. 7 is a top plan view of the full body resistance bar with wheels shown in FIG. 1; and,

FIG. 8 is a bottom plan view of the full body resistance bar with wheels shown in FIG. 1.
